UNITED STATES PATENT OFFICE.

THOMAS J. BUCKLEY, OF NEW BRUNSWICK, NEW JERSEY.

MACHINE FOR PRINTING TUBES.

1,128,753.

Specification of Letters Patent.

Patented Feb. 16, 1915.

Application filed January 14, 1914. Serial No. 812,135.

To all whom it may concern:

Be it known that I, THOMAS J. BUCKLEY, a citizen of the United States, and a resident of New Brunswick, in the county of 5 Middlesex and State of New Jersey, have invented certain new and useful Improvements in Machines for Printing Tubes, of which the following is a specification.

The invention relates to machines for 10 printing metal containers and other articles in cylindrical or tubular form, and its objects, among others, are to produce a device of this character of simple, durable and effective construction and operation to 15 provide for a higher efficiency and a better quality of work, and to provide for various adjustments of the parts to that end.

The improvements reside in the construction and arrangement of parts hereinafter 20 described and claimed and illustrated in the accompanying drawings.

In the said drawings, Figure 1 is a side elevation of a machine embodying the improvements. Fig. 2 is an enlarged elevation 25 of certain parts of the machine viewed from the opposite side to Fig. 1. Fig. 3 is a plan of some of the parts shown in Figs. 1 and 2.

The framework of the machine consists 30 of two parallel upright frames 1 and 2 spaced apart and having recesses 3 and 4 therein, in which are adjustably mounted sliding journal blocks 11 and 12 provided with adjusting screws 13 and 14, and 35 springs also mounted in the frames, for moving the same. In these journal blocks rotate the ends of the shafts on which the bed-plate roller 20 and inking roller 21 (see dotted lines Fig. 1) are mounted. The 40 shafts on which other rotary members of the machine are mounted also have their journals in the said frames; the journal at one end being mounted in the frame on one side and the journal at the other end being 45 mounted in the opposite frame. This includes the pulley shaft 22, the cam shaft 23, the segment gear shaft 24 and the idler shaft 25.

Ink is supplied to suitable rollers 26, 27 50 and 28 mounted in vertical slots in the supplemental upright frames 5, and the lowermost of these rollers, 28, are in contact with the large inking roller or cylinder 21, which

is driven from the pulley shaft 22 through the idler 25—as is also the bed-plate roller 55 20. In this manner the plate 30 on the cylinder or roller 20 is supplied with ink.

The cylinder 20 may be provided with any suitable means for securing and adjusting the plate 30 which bears intaglio or bas 60 relief figures adapted to print an impression on the tube 40 on the mandrel 41, which is adapted to be rotated when in printing position by the shoe 31^a on one end of the cylinder 20 which is preferably made of 65 rubber or other compressible material so as to prevent slipping.

There are three mandrels 41, and each is a hollow tube with closed outer end mounted on a non-rotating post 42, and furnished 70 with ball bearings 43 at its base and 44 at its outer end. The posts 42 are in turn eccentrically mounted on a disk 45 on the rotary head 46, and are adapted to be moved intermittently through an arc of 120 degrees with the said head. The eccentric mounting of the posts provides a limited adjustment of the mandrels to take up wear and for other purposes.

The step by step rotation of the head is 80 brought about by means of the pawls 50 which have a reciprocating motion and engage the ratchets 51 of the disk 51^a secured to and rotating freely with the head 46. Motion is imparted to them through the 85 pinion 52 keyed to the same shaft, 53, therewith, the horizontal rack 54 on the upper edge of the sliding bar 55, which engages the said pinion, and the corresponding rack 56 in the lower edge thereof at the opposite end and the segment 57 which is given oscillating movement by the heart cam 58 rotated by the shaft 23, upon which it is keyed. The cam 58 receives its rotary motion from the drive shaft 22 through the 90 idler 29 which meshes with the gear 32 and the gear 33 keyed to the cam shaft, and the roller 59 mounted on a stud on the segment 57 engages the cam. The cylinder gear 31 also meshes with the gear 33 and in this 95 manner receives its motion from the drive shaft. The sliding bar 55 is mounted in the guides 60 and 61.

In order to adjust the mandrels or spindles 41 so as to secure a perfect alinement 100 with the plate and thus secure an even im-

pression on the tube the head 46 is mounted so that it can be moved bodily to and from the said plate and also oscillated so as to bring about perfect parallelism between the face of said plate and the exterior surfaces of the tubes. This is provided for in the following manner: The head plate 46 is mounted in one end of a casing 47 of the head, and in the other end of this casing is mounted a plate 48 through which the inner offset ends 44^a of the posts 42 extend, being secured by means of suitable nuts 49. This casing is mounted on a round swivel foot 34 working in the socket 35, and is provided with a clamp 36 by which it may be secured in any desired position. This clamp extends through the base 37 of the casing adjacent to the foot 34, and a depending portion of the base is provided at one end in which the adjusting screw 38 extending into a threaded aperture of the frame is mounted. This screw 38 is used to move the casing bodily, and the mandrels, to and from the cylinder 20. Other adjusting screws 39 and 39^a extend through the base 37 at right angles to the screw 38 and bear against a depending portion of the head casing to give the casing and the mandrels the oscillating movement on the said base. The entire base of the casing 37 and the parts supported thereon slide on the dovetail track 34^a on the frame in a corresponding slide way 37^a in the bottom of said base, and may be secured at any point by the clamp 36.

In order to hold the tubes in the printing position while the actuating pawls 51 are being retracted, and maintain them, the shaft 53, on which the disk 51 bearing the ratchets 51 is mounted, has keyed thereto a cam 15 against which is pressed a roller 6 on a rocking arm 16 by means of a spring 7, and a bolt 17 is pressed by a spring 8 into notches 18^a of another disk 18 keyed to the said shaft, when the said arm 16 reaches the bottom of the inclined side of the cam, if the said bolt and one of the notches are in alinement. The cam is so located that it will cause the rocking arm 16 to retract the bolt, through contact of an extension 9 with a roller 19 on the bolt, at the end of the backward movement of the spring pawls 50 and permit the same to engage the said notches at the end of the forward movement and remain in such engagement until the end of the next backward movement. As the outer end of the rocking arm 16 moves inward at the beginning of the forward motion, the bolt 17 must ride on the outer edge of the disk 18 until another notch 18^a is brought into alinement therewith, which occurs at the moment the tube reaches printing position. The spring 8 which constantly presses the bolt 17 forward is held in a tubular recess in the shank

of the bolt, between the inner end of the said recess and the plate 10. In this manner each tube is held in position while the plate is passing over its surface and then moved to a lower position while another is moved into its place, and each mandrel is held stationary while its tube is being printed, removed and replaced.

The operation of the machine will be fully understood by those skilled in the art from the foregoing description.

Various modifications of the structural details of the machine may be made, and some of the parts may be changed, omitted or replaced by other parts without departing from the scope of the invention.

What I claim is:

1. In a device of the character described, the combination with driving mechanism, a cylinder adapted to carry a plate for printing an impression and an inking device of a plurality of spindles adapted to carry tubes to be printed, means for moving the said spindles automatically into and out of proximity to said cylinder and an operative connection between said spindles and said cylinder, and means for adjusting the position of said spindles and tubes with respect to the surface of the cylinder individually and collectively.

2. In a device of the character described, the combination with driving mechanism, a cylinder adapted to carry a plate for printing an impression and an inking device of a plurality of spindles adapted to carry tubes to be printed, means for moving the said spindles automatically into and out of proximity to said cylinder and an operative connection between said spindles and said cylinder, and means for adjusting the said spindles and tubes carried thereby with respect to the surface of the said cylinder, comprising a head upon which they are mounted, means for moving the said head bodily and means for oscillating the same, and means for fixing the said head in various positions to which it may be so moved.

3. The combination of a movable bed-plate adapted to carry a printing plate, inking devices for inking said printing plate, a rotary post or spindle adapted to hold a tube to be printed, and means for moving the same bodily to and from the printing plate, means for moving the same bodily in a direction at an angle to said to and from the plate movement, and additional independent means for adjusting its position with respect to said plate.

4. In a machine of the character described, the combination of a device for carrying printing type or the like, means for inking the same, a plurality of holders adapted to receive and carry tubular articles to be printed and means for present-

ing the said holders successively to the printing surface, and means for adjusting the position of the said holders with respect to the printing surface vertically and horizontally and obliquely.

5. In a machine of the character described, the combination of a device for carrying printing type or the like, means for inking the same, a plurality of holders adapted to receive and carry tubular articles to be printed and means for presenting the said holders successively to the printing surface, and means for adjusting the position of the said holders with respect to the printing surface vertically and horizontally and obliquely with respect to the line of one of the other adjustments.

6. In a machine of the character described, the combination of a device for carrying printing type or the like, means for inking the same, a plurality of holders adapted to receive and carry tubular articles to be printed and means for presenting the said holders successively to the printing surface, and means for adjusting the position of the said holders with respect to the printing surface individually in a horizontal and vertical direction, and collectively in a horizontal direction and to various positions in a horizontal plane angular to the printing surface.

7. In a machine of the character described, the combination with a printing device comprising a holder for a printing plate or the like, and means for inking the same, of a carrier for a tubular article to be printed, means for moving said carrier to and from the printing plate for the purpose of printing an impression thereon, and means for adjusting the said carrier so as to present the said article to the plate at different angles to the printing surface, and a plurality of independent means for adjusting the pressure of contact between the article to be printed and the said printing surface.

8. In a device of the character described, the combination of a printing device, a plurality of carriers adapted to carry tubular articles to be printed, means for moving the said carriers so as to bring the said articles into and out of contact with the printing device and automatic means for locking the said carriers in position adjacent to the printing device and in position removed therefrom, and means for automatically unlocking the same, all of said means being operatively connected and arranged to lock at the beginning of the printing operation of each article and unlock at the end of said printing operation, and means for adjusting the said carriers individually and collectively with respect to the printing device.

9. The combination of a printing device, a series of tube carriers, a rotating member 65 on which the said carriers are mounted and

from which they project, and means for moving the said member on which the carriers are mounted and the carriers to and from the printing device and for fixing the same in different positions in the said line 70 of movement, and means for moving the said member to different positions angular to the line of the said first movement and for fixing it in said positions, whereby the carriers may be adjusted to and from the 75 printing device and to bring the tubes carried thereby into exact parallelism longitudinally with the same.

10. The combination of a printing device, a plurality of carriers adapted to carry tubular articles to be printed, means for moving the said carriers to and from the printing device, said carriers being movably mounted, and means for causing the said carriers to move individually while in position adjacent to the printing device, and means for adjusting the said carriers independently with respect to the printing device and for fixing them in different positions to which they are so adjusted. 80

11. The combination of a plurality of supports, a head on which the same are mounted and from which they extend, a base upon which said head is mounted, said base having longitudinal and swinging movement, means for moving said head and the supports mounted thereon in such a manner as to present the said supports and the articles to be printed thereon successively at a printing position, a locking device constructed and arranged to automatically lock the said head against movement when a support reaches the printing position, and means for automatically releasing the said head from said locking device after it has 100 stood with the carrier at the printing position a predetermined period, said locking and unlocking means comprising a member provided with a plurality of sockets in fixed relation to the head, an independently 105 movable cam member mounted on said base, a common means for moving the said member and the head and means mounted on said base with said head and adapted to move therewith for permitting the locking device to 110 move into locking position, said cam member causing the locking device to move out of locking position.

12. The combination of a plurality of supports, a head on which the same are mounted and from which they extend, a base upon which said head is mounted, means for moving said head and the supports mounted thereon in such a manner as to present the said supports and the articles to be printed thereon successively at a printing position, a movable printing plate and bearings between the said supports and the head upon which they are permitted to rotate freely, and means for causing the said supports to 120 125 130 135

rotate while at the printing position, said means comprising a movable member independent of the printing plate, with which the said supports are adapted to come in contact at the printing position.

Witness my hand this 9th day of January 1914, at the city of New Brunswick, in the

county of Middlesex and State of New Jersey.

THOMAS J. BUCKLEY.
